IMITATION FIRING MECHANISM FOR
TRAINING ARMS

William G. Dunn, Clarinda, Iowa

Application January 8, 1943, Serial No. 471,741

3 Claims. (Cl. 42—69)

1

My invention relates to an improved form of training arm, as used for military purposes in training new men.

In many instances it is undesirable to put an operative rifle into the hands of recruits who have had no training or instruction in the care and use of such arms. But for practice and drill purposes, it is desirable to provide an inexpensive arm which will correspond closely to a standard weapon in appearance, size and weight, and it is further advantageous if such an arm incorporates certain operative features which will enable the carrying out of the customary manual of arms drill. Specifically, it is desirable to have an operative bolt action and a trigger mechanism which is cocked by operation of the bolt.

It is an object of my invention to provide a training arm having the advantageous features just outlined.

It is a further object to provide a bolt action mechanism capable of being produced by relatively low cost manufacturing methods.

It is a further object of my invention to provide a trigger action, cocked by operation of the bolt, and releasable by pulling the trigger, with a feel and a click sound simulating the action of a rifle that will shoot.

It is a further object to provide a trigger action mechanism which can be cheaply assembled from cast parts without the necessity of machining operations, and which requires only a single spring.

With these and other objects which will become apparent as the description proceeds, my invention consists in the construction, arrangement and combination of the various parts of my device whereby the objects contemplated are attained, as hereinafter more fully set forth, pointed out in my claims and illustrated in the accompanying drawings, wherein:

Figure 1 is a side elevational view of a training arm embodying my invention;

Figure 2 is a top view of the same;

Figure 3 is a fragmentary sectional view of the fore part of the arm, on a somewhat larger scale than Figure 1;

Figure 4 is a vertical sectional view taken on the line 4—4 of Figure 2 and Figure 5;

Figure 5 is a fragmentary view of the trigger action and a part of the bolt, the view being partly in elevation and partly in vertical section on the line 5—5 of Figure 4;

Figure 6 is a view similar to Figure 5, but shows the parts of the trigger mechanism in cocked relation;

2

Figure 7 is a perspective view showing the main casting of the trigger mechanism, and the two principal operating members, in exploded relation;

5 Figure 8 is a fragmentary horizontal sectional view taken substantially on the line 8—8 of Figure 6;

Figure 9 is an enlarged plan view of the portion of the arm including the bolt action, parts being 10 broken away to show the construction;

Figure 10 is a development, showing the blank from which the bolt housing is made up, and

Figure 11 is a fragmentary vertical sectional view, taken on the line 11—11 of Figure 9.

15 In the drawings, the reference numeral 10 indicates generally the wooden stock, which may be provided with a regulation sling strap 12. Around the stock are bands 14 and 16, each carrying sling loops 18 on fittings 20, these parts corresponding 20 to those on the prototype arm which my training arm simulates. On the under side of the band 16 is a bayonet fitting 22. The barrel 24 consists of a short length of rod, with a hole, indicated in dotted lines at 26, drilled at the outer end to simulate the bore. The rod extends into a hole 28 in the stock and is retained by a screw 30 which fastens the band 16 and its accompanying fitting 20. This screw extends into the barrel 24, as indicated in Figure 3. If the barrel is made of 25 metal, a countersunk or shallow drilled hole 32 may be provided to receive the end of the screw. If the barrel is made of wood, this is not necessary. The barrel may be provided with a front sight 34.

30 The portion marked 36 in Figure 1 is formed as a part of the wooden stock, but is painted black, to correspond to the blued metal parts which are found in the prototype at this point. A leaf type rear sight 38 may be mounted on the top, in the 35 customary manner.

40 The bolt action of my training arm, indicated generally by the numeral 40, consists principally of a bolt 42 having an operating lever 44 attached to a cam 46 at the rear end of the bolt. The bolt is slidably mounted in a housing 48, and at the forward portion of its movement bears against a coil spring 50 which is mounted in the stock, as shown in Figure 9.

45 The housing I form from a heavy sheet metal blank 52 having an outline such as that illustrated in Figure 10. The blank is bent along the dotted lines 54 and 56 to form the angles 58 and 60, respectively, as seen in the cross-sectional view of Figure 11, and the tongues 62 and 64 are 50 curved to fit across the top of the bolt, meeting

the similarly curved edge 66 of the blank, as may also been seen in Figure 11. The formed-up housing has a flat bottom, so that it may be easily and firmly mounted by screws 51 in the notch provided for it on the top of the stock.

The shape of the blank leaves an elongated slot 68 on the top side of the housing when it is formed up as described. A fillister head screw 70 is carried by the bolt 42, the diameter of the head being such as to occupy substantially the full width of the rear portion of the slot. In its forward portion, the right hand side of the slot, as the gun is viewed from the rear, is widened by reason of the additional cut-out 72 in the blank.

The screw 70 is located on the bolt at such a point that, as the bolt is slid forward, the spring 50 must be compressed somewhat before the bolt head can pass around the corner 74 of the housing, when the bolt lever 44 is moved downward. Thus, when the bolt is rotated by pressing down on the lever, the head of the screw 70 moves downward into the notch 76. A portion 78 of the edge of this notch is inclined slightly toward the rear, so that the bolt is locked in the notch under the influence of the spring 50. The result is a bolt action which has a "feel" very closely resembling that of a gun that will shoot.

For economy in the use of metal, I prefer to make the bolt itself as a metal tube 80, formed up, like the housing 48, from a flat sheet. In training arms using such construction I have found it advisable to fill the tube with a wooden plug 82, both to give a square surface on the forward end of the bolt for adequate bearing against the spring 50, and also to extend rearwardly as the member 84 simulating the cocking piece on an operative rifle. Wooden parts such as this may be given a black or blued finish to imitate the metal parts which they are supposed to represent.

The trigger action of my practice arm is particularly illustrated in Figures 4-8. The trigger mechanism is made particularly convenient for economical manufacture by reason of its arrangement as a subassembly carried on the main casting or frame 86, which has a side wall portion 88 and end wall portions 90. It carries the trigger guard 92 and mounting ears 94. The operative parts of the trigger mechanism consist of the trigger 96 and the member 98 which I shall refer to as the hammer. The main frame 86 has mounting posts 100 and 102 cast integral therewith, and the hammer and trigger elements have cored holes 104 and 106 fitting over the posts. Recesses 108 and 110 are provided in these elements to receive and retain a coil spring 112, which is under compression at all times when in its working position. By reason of the relation of the recesses 108 and 110 to the pivot holes 104 and 106, the spring tends to rotate both the hammer member and the trigger member in clockwise directions, as viewed in Figures 5 and 6. The main frame carries a stop 114 which limits clockwise rotation of the hammer member 98.

The parts 86, 96 and 98 can be made up as castings in the form shown in Figure 7 and, if properly made, they need no further machine operations other than tumbling to clean them and remove sharp edges.

The trigger and hammer are put in place on the mounting posts and the spring 112 is pressed into its recesses. The open side of the mounting plate 88 is then covered by a simple sheet metal plate 116 having side flanges 118 and 120 which overlap the end walls 90 of the main frame, and

are frictionally retained thereby. The entire assembly can then be slipped into a mortised recess in the gun stock, where it is retained by screws 122. An extension 124 of the mortised recess 5 opens onto the top side of the stock, and permits coaction between an extended head 128 on the hammer and the cam 46 on the bolt.

The trigger member 96 has a recess 130, and the hammer member is provided with a projecting pawl 132 adapted to coact therewith. When the trigger is pulled, it rotates counterclockwise as viewed in Figure 5, and releases the pawl 132 so that the hammer member can move clockwise, allowing the head 128 to strike against the cam 46, which gives a sharp click, very similar to that occurring in the regulation rifle when the trigger is pulled.

In Figure 4, the lever 44 is shown in full lines in the position it normally occupies after the gun is cocked. After the trigger has been pulled, the lever is raised to the dotted line position of Figure 4, which swings the lobe 134 of the cam across the head 128 of the hammer member, depressing the head and thus rotating the hammer member counterclockwise, as viewed in Figure 5, to the point where the notch 130 slips over the pawl 132, the force of the spring tending always to move the trigger 96 into latching engagement with the pawl. The trigger mechanism is then in cocked condition, as illustrated in Figure 6. The bolt 10 may be slid rearwardly, as if to expose the chamber in the usual inspection routine, and may then be slid back and rotated again to the full line position of Figure 4. As I have indicated, the gun 20 is then cocked and pulling the trigger will release the hammer member. The shape of the cam is such that in the normal locked position of the bolt the head 128 of the hammer member will engage the cam before the hammer member is impeded by the stop 114. This is not a feature of 30 substantial importance since a sharp click is obtained in either case, but it sounds more like the real thing when the impact takes place against the cam on the bolt.

In addition to the fact that the single spring 35 supplies the force both for operating the latch and for actuating the hammer, my structure has the advantage that pulling the trigger further compresses the spring. As a result, the trigger "feel" is very similar to that of an actual rifle; also, after the latch is disengaged when the trigger is pulled, the further movement of the trigger lever is such as to follow the spring, tending to keep the force against the hammer from decreasing, and giving a good snappy action.

A substantially flat bearing surface 136 is formed on the trigger 96 adjacent the notch or recess 130, to lie against the pawl 132 when the latter is not engaged in the recess. The bearing surface is of such extent as to follow the pawl to the extreme limit of the hammer movement as determined by the stop member 114. When the hammer is being cocked, the pawl slides freely back along the surface 136 until the recess 130 is reached; when the recess receives the pawl, the hammer is cocked.

From the foregoing description, it will be seen that I have devised a structure adequately fulfilling the various objects originally set forth. The arm made as described may be employed for ordinary drill purposes, and in such use will simulate the desired operative functions of a real rifle. Yet it can be manufactured at very low cost, eliminating any necessity of subjecting the more expensive equipment to carelessness or misuse.

Some changes may be made in the construction and arrangement of the parts of my device without departing from the real spirit and purpose of my invention, and it is my intention to cover by my claims any modified forms of structure or use of mechanical equivalents which may be reasonably included within their scope.

I claim as my invention:

1. In a training arm, a stock having a recess in its under side, a mounting plate in the recess, a trigger pivoted to the plate and having a forwardly projecting portion provided with a recess in its top, and an upwardly projecting part with a recess in its front edge, a hammer pivoted to the plate above the trigger and having a recess below the horizontal line through the hammer pivot facing the last recess, and a spring seated in the last two named recesses, said hammer having a latching lug for sliding on said forwardly projecting portion and cooperating with the recess therein, said hammer having a forwardly and upwardly extending head adapted for cooperation with the breech bolt of the training arm, whereby the "click" of a firearm is simulated.

2. In a training arm, a cocking mechanism, including a mounting plate, a trigger pivoted to the plate and having a forwardly projecting portion provided with a recess in its top, and an upwardly projecting part, a hammer pivoted to the plate above the trigger and having a recess below the horizontal line through its pivot facing the said

upwardly projecting part, and a spring interposed between the bottom of the recess in the hammer and the upwardly projecting part of the trigger, said hammer having a latching lug for sliding on said forwardly projecting portion and cooperating with the recess therein, said hammer having a forwardly and upwardly extending head adapted for cooperation with the breech bolt of the training arm, whereby the "click" of a firearm is simulated.

3. In a training arm, a cocking mechanism, including a mounting plate, a trigger pivoted to the plate and having a forwardly projecting portion provided with a recess in its top, and an upwardly projecting part, a hammer pivoted to the plate above the trigger and having a recess below the horizontal line through its pivot facing the said upwardly projecting part, and a spring interposed between the bottom of the recess in the hammer and the upwardly projecting part of the trigger, said hammer having a latching lug for sliding on said forwardly projecting portion and cooperating with the recess therein, said hammer having a forwardly and upwardly extending head adapted for cooperation with the breech bolt of the training arm, whereby the "click" of a firearm is simulated, said mounting plate having a stop lug overhanging the hammer to limit its pivoted movement away from the trigger.

WILLIAM G. DUNN.
